[57] CLAIM

The ornamental design for a portable tray for tumblers and bowl, as shown and described.

DESCRIPTION

FIG. 1 is an upper right side perspective view of a portable tray for tumblers and bowls showing our new design;

FIG. 2 is a front end elevational view of the tray shown in FIG. 1;

FIG. 3 is a right side elevational view thereof, the left side being identical thereto;

FIG. 4 is a back end elevational view thereof;

FIG. 5 is a top plan view thereof; and,

FIG. 6 is a bottom plan view thereof.
